UNITED STATES PATENT OFFICE.

EDWARD B. JACOBSON, OF PITTSFIELD, MASSACHUSETTS. ASSIGNOR TO J AND B MANUFACTURING COMPANY, OF PITTSFIELD, MASSACHUSETTS, A CORPORATION OF MASSACHUSETTS.

IGNITION-TIMER.

1,371,972.

Specification of Letters Patent.

Patented Mar. 15, 1921.

Application filed September 13, 1919. Serial No. 323,572.

To all whom it may concern:

Be it known that I, EDWARD B. JACOBSON, a citizen of the United States, residing at Pittsfield, in the county of Berkshire and 5 State of Massachusetts, have invented certain new and useful Improvements in Ignition-Timers, of which the following is a specification.

The present invention relates to ignition 10 timing apparatus adapted for use in connection with explosive engines, and particularly concerns structural improvements in the brush or contact-roll and its mounting carried by the rotary portion.

15 The primary object of the invention is to simplify the construction and to increase the efficiency and durability of the device, and these results are accomplished by the construction, combination and arrangement 20 of parts as hereinafter described and shown and set forth in the claims.

Referring to the accompanying drawings,—Figure 1 is a longitudinal vertical section of an ignition timer embodying the 25 present invention and operatively mounted upon a driven shaft; Fig. 2, a face view of the same, the front portion of the housing being cut away; Fig. 3, a longitudinal vertical section of the rotor portion mounted 30 as shown in Fig. 1, with the casing removed; Fig. 4, a vertical cross-section of the rotor assembly on a plane coincident with the inner face of the outer radial carrier-arm; Fig. 5, a cross-sectional view of the outer 35 end of the contact-arm through the center of the brush or contact-roll; Fig. 6, a detail side elevation of the contact-roll supporting pin; and Fig. 7, a bottom plan view of the contact arm.

40 The mechanism herein illustrated is designed for use in connection with a four-cylinder explosive engine having a gear-driven cam-shaft operated by the main engine shaft, but it should be understood, however, that the invention is applicable for 45 use with motors having a different number of explosive cylinders, and may be otherwise mounted and driven.

This invention may be adapted to any 50 suitable form of housing or casing, the casing 1 herein illustrated being adjustably mounted on the front of the engine housing 2 and arranged to inclose the front end of a

cam-shaft 3, which is preferably geared to the main engine shaft (not shown) and extends through a suitable opening in the wall 55 of the engine housing.

The rear end of the casing 1 is open and seated in a circular recess 4 provided on the face of the engine housing 2, said recess being adapted to prevent eccentric displacement of the casing. Forward displacement of the casing is prevented preferably by a spring clamp 5 removably secured at its rear end to a stud or bolt 6 fixed to the wall 60 of the engine housing 2, and engaging at its 65 opposite end the outer extremity of the reduced forward extension of the front of the casing, which has a central depression to receive a boss 7 provided on the clamp 5. 70 Axial movement of the casing for regulating the time of ignition is controlled by a lateral arm 8 exteriorly mounted on the casing and provided with a bearing 9 to receive a control-rod (not shown). 75

Within the casing 1 is an insulation ring 10 provided at regular intervals with arcuate contacts 11, 11, which are embedded on the inner rim and suitably connected to separate terminals 12, 12, etc. arranged on the 80 outside of the casing 1, for connection with the primary circuit of separate induction coils.

Mounted to rotate with the shaft 3 within the casing 1 is a metallic carrier 13 in a 85 form of a sleeve which is normally secured against axial movement on the shaft by a transversely arranged removable pin 14 projecting through a suitable opening in the shaft and extending at one of its ends into 90 a slot 15 provided on the outer rim of the carrier. The pin 14 is secured against endwise displacement by a cup washer 16 fitted over the outer end of the carrier and inclosing the exposed end of the pin, the reduced 95 outer end 17 of the shaft being projected through the cup washer 16 and suitably threaded to receive a pair of nuts 18, 19, which are employed in conjunction with a flat washer 20, carried on the reduced end 100 of the shaft and engaging the face of the cup washer, to secure the latter in position.

The carrier 13 is provided with a pair of fixed radial arms 21, 21, arranged in spaced parallel relation to each other and pivotally supporting at their outer ends a contact- 105

arm comprising a pair of oppositely arranged plates 22, 23, which are secured at their inner ends to the arms by a transversely arranged pin 24 extending into suitable openings provided in the plates, one end 25 of said pin being preferably reduced to provide a shoulder bearing against the outer plate 22 to prevent displacement of the pin outward, displacement of the pin in the opposite direction being prevented preferably by burring said end 25 at its outer extremity.

As shown, the plates 22, 23, are curved in outline and secured together centrally by an integral yoke or bridge member 26. Transversely arranged in the jaw formed by the plates 22, 23, at the free end of the contact-arm is a stationary case-hardened bearing-pin 27 extending at opposite ends into suitable openings in the plates, the outer plate 22 being preferably thickened at this point. To prevent rotation in its bearings the pin 27 is knurled or milled at its outer end (see Figs. 5 and 6) and driven into the opening provided in the plate 22, while endwise displacement of the pin in either direction is prevented preferably by means of an annular groove 29 provided on said outer end, a prick punch being employed after setting of the pin to force portions of the metal of the plate 22 at opposite points 30, 30, into said groove.

Revolutely mounted on the bearing-pin 27 is a brush or roller 31 adapted to be swung on the contact-arm toward and away from the carrier 13 and arranged normally to travel upon the inner rim of the insulation ring 10 for successive engagement with the contact-elements 11, 11, etc. A yielding contact of the roller 31 with the ring 10 is provided by means of a torsion-spring 32, which is carried centrally upon the contact-arm supporting pin 24 and operates normally to impel the outer end of the contact-arm outward, one end of the spring being arranged to bear against the underside of the bridge member 26 and the opposite end against the carrier 13. (See Fig. 4.) When the rotor assembly is removed for any reason from the cam-shaft 3, the outward spring of the contact-arm under the impulse of the spring 32 is limited by positive stops in the form of arcuate shoulders 33, 33, peripherally arranged on opposite sides of the carrier 13 and adapted to be engaged at the predetermined point of movement by inwardly extending feet 34, 35, provided on the inner margins of the plates 22, 23.

Undue wear of the engaging parts is prevented by the application of a suitable fluid lubricant in accordance with the usual practice, the lubricant being preferably intro-

duced into the casing through a closable inlet 36 provided in its front wall.

The essential merits of the foregoing invention reside principally in the simplicity of structure, rigidity and durability of the contact-arm and the roller mounting. These features are designed to prevent displacement of parts and undue or unequal wear on the roller and roller pin.

I claim:

1. In an ignition timer, the combination with a rotor portion, including a carrier having lateral extension members; of a brush-supporting arm pivoted on said extension members and having a free end arranged to swing toward and away from the carrier, said arm being formed of oppositely arranged plates rigidly secured together by a bridge-member forming an integral connection with each of the plates and having a web designed to oppose the spreading of the plates at their inner margins.

2. In an ignition timer, the combination with a rotor portion having a lateral extension portion, of a contact-roll supporting arm pivoted on said extension portion and having a free end forming a pair of jaws arranged to swing toward and away from the carrier; an axle mounted to extend at opposite ends into openings provided in said jaws, said axle being milled on at least one end and designed to be driven into the jaw to prevent rotation of the axle; a contact-roll rotatably mounted on said axle; and locking means for positively preventing endwise displacement of the axle.

3. In an ignition timer, the combination with a casing and contact-elements mounted in the casing; of a rotor portion mounted to move in the casing, and comprising a carrier; an arm on the carrier; a separate arm pivoted to said carrier arm and having a free end provided with an apertured jaw adapted to swing toward and away from the contact-elements; an axle extending at opposite ends into the sides of the jaw and having an annular groove in one end; a registering member provided on the margin of the opening in one side of the jaw and arranged to take into said groove in the axle to prevent endwise displacement of the axle; a roller mounted to rotate on the axle; and means for normally impelling the free end of the pivotal arm outward for successive engagement of the roller with the contact-elements.

In testimony whereof I hereunto affix my signature.

EDWARD B. JACOBSON.
